VALVE

Howard A. Rike, Fort Worth, Tex.

Application July 12, 1937, Serial No. 153,195

12 Claims. (Cl. 123—188)

This invention relates to new and useful improvements in valves.

One object of the invention is to provide an improved valve structure which may be readily installed in the intake chamber of a gas engine to control the admittance of fuel to said engine.

An important object of the invention is to provide an improved valve structure including a valve head which is arranged to be mounted in the intake chamber of a gas engine in place of the usual large single valve; said head having a plurality of relatively light valves mounted therein, whereby battering or marring of the valve seat due to the pounding action of a large valve, which is relatively heavy, against said seat is eliminated.

Another object of the invention is to provide an improved valve cluster which is adapted to be substituted for the usual single intake valve of a gas engine, wherein a plurality of relatively light valves control the admission of fuel, said valves being actuated by the engine suction and due to their light weight are quick opening and closing, whereby fuel waste is minimized; each valve being individually mounted in the assembly to permit its repair or replacement without affecting the other valves.

A further object of the invention is to provide an improved valve cluster of the character described, wherein the stroke of the individual valves is limited which eliminates hammering or pounding of said valves in operation; said valves being arranged to seat on a head forming part of the assembly, whereby operation of the valves causes no appreciable wear on the engine valve chamber.

A construction designed to carry out the invention will be hereinafter described, together with other features of the invention.

The invention will be more readily understood from a reading of the following specification and by reference to the accompanying drawing, in which an example of the invention is shown, and wherein:

Figure 1 is a transverse, vertical, sectional view of the intake chamber of a gas engine having a valve assembly constructed in accordance with the invention mounted therein.

Figure 2 is a plan view of the valve assembly.

Figure 3 is a transverse, vertical, sectional view taken on the line 3—3 of Figure 2.

Figure 4 is an enlarged horizontal, cross-sectional view, taken on the line 4—4 of Figure 1, and

Figure 5 is a bottom view of the assembly.

In the drawing, the numeral 10 designates the intake valve chamber of a gas engine which may be of any usual construction, such as may be purchased on the open market. The particular engine to which the invention is applied is sub-

ject to variation, as it has been found that the same is readily mounted in any of a number of standard gas engines, namely, "Bessemer", "Superior", "Marion", "J. C.", and "Reid". The valve chamber is provided with a transverse partition 11 located at substantially mid-height therein and an opening 12 in the top of the chamber establishes communication between the interior of the chamber and the combustion chamber of the engine (not shown). A horizontal inlet port 13 extends through the wall of the casing below the partition 11 to admit the fuel mixture into the chamber 10, while a central cylindrical opening 14 is formed in the partition, whereby the fuel mixture may flow upwardly through said opening 14 and chamber, from where it is conducted to the engine. Manifestly, by controlling the flow through the opening 14 in the partition 11, the fuel mixture admitted to the engine is controlled.

The upper portion of the opening 14 is enlarged to form an annular seat 15 and it has been the usual practice to employ a single valve adapted to engage the seat. Such a valve is guided in its movement by a depending stem 16 which is slidable in a sleeve or collar 16 extending upwardly from the bottom of the chamber 10. The single valve is comparatively heavy in weight and since engine suction is depended upon to raise said valve, the operation of the same is relatively slow. Also, the weight of the valve causes the same to seat with a great deal of force which batters the seat 15, resulting in a poor seating engagement with the valve. When said seat does become worn, it is necessary to either replace the entire intake chamber or remove the same from the engine to repair it. Further, wear of the valve itself requires replacement of the entire valve.

To overcome the disadvantages of a single valve such as is now in common use, a cylindrical valve head 17, is inserted within the opening 14 and is supported on the annular shoulder 15, as is clearly shown in Figure 1. An axial shank 18 depends from the head, being preferably made integral therewith, and said shank extends below the bottom of the partition 11 into the lower end of the chamber 10. An axial stem 19 has its upper end threaded in the bottom of the shank, while its lower end is inserted within the upwardly extending sleeve or collar 16. The bore of the sleeve is threaded to receive the lower threaded end of the stem and manifestly, the stem acts to securely fasten the head 17 on the seat 15.

A plurality of openings or ports 20 extend vertically through the head, being preferably located an equal distance apart around the head. As is clearly shown in Figures 2 and 3, the openings are disposed between the periphery of the head and

the shank 18, and establish communication between the upper and lower portions of the chamber 10 on each side of the partition 11. The ports may vary in number according to the H. P. of the gas engine and although four have been illustrated in the drawing, the invention is not to be limited to any particular number.

For controlling the flow of fuel through the ports 20, a plurality of valve members 21 are provided. Each valve member is arranged to close one of the ports and since all of the members and ports are exactly alike, a description of one member and its engagement, with its respective port will suffice. Each valve member includes a valve disk 22 having an annular bevel 23 on its underside at its marginal portion. The upper end of each port is formed with a complementary bevel to form a seat 24 arranged to be engaged by the bevel of the valve disk. A valve stem 25, preferably integral with the disk, depends axially from the underside of said disk and passes through a vertical bore or opening 26 formed in a radially extending guide boss or collar 27. The guide collar is preferably made integral with the lower end of the shank 18 and as clearly shown in Figure 4, a guide collar is provided for each valve member and is so positioned that the stem 25 of said member passes through the bore thereof. A suitable guide sleeve 28 is inserted in the bore 26 of each boss or collar and surrounds the stem. The sleeve has an annular flange 29 at its lower end which flange abuts the underside of the boss when in position within the bore.

The lower end of each stem 25 extends below its boss or collar and is enlarged as shown at 30, whereby a flanged ring 31 may be slidably confined on the stem. A coiled spring 31' surrounds each stem, being confined between the ring 31 and the underside of the boss or collar, and constantly exerts its pressure to urge the valve member downwardly with the disk 22 engaging the seat 24. Thus, said springs tend to hold the valve members in a closed position, whereby communication between the lower end and the upper end of the chamber is prevented.

Manifestly, the valve members 21 control the flow of the fuel mixture to the combustion chamber of the gas engine (not shown) and the size of the ports 20 is such that their combined area admits sufficient fuel when the disks 22 of the members are unseated. The suction of the engine acts upon the upper surface of the disks to unseat the same under tension of the coiled springs 31' and since the valve members are relatively light, said suction quickly opens the members. Similarly, when the suction is relieved, the springs 31' immediately seat the disks to close the openings. The lightness of the members obviates the pounding or hammering action against their seats which prolongs the life of both the seats and disks.

To limit the upward movement of the valve members 21 so that the suction does not raise said members farther than is necessary, a spider 32 is formed with a central depending collar 33, which collar rests on the top of the head 17 at the central portion thereof. The spider arms 34 overhang the disks 22 of the valve members 21 and a stud bolt 35 passes through a vertical axial bore 36 formed in the spider and collar and is threaded into the head 17. Obviously, upward movement of the members is limited by the disks 22 striking the spider arms 34. It is noted that other means for limiting the upward movement of the members may be employed, such as providing a projection on the stem 25 arranged to strike the underside of

the boss and therefore, the invention is not to be limited to any particular type of stop means.

From the above, it will be seen that a plurality of small, relatively light valves are mounted in a single assembly which is substituted for the usual single valve. The valves are positive in operation being quick opening and closing, which results in fuel saving and more efficient engine performance. Further, the valve disks and seats are not subject to severe pounding or hammering action because of the lightness in weight of the valves and also because of the limited movement which the valves undergo. If any one of the valve members become worn, it can easily be replaced without affecting the other valve members. Also, if the seats become worn the assembly may be removed and said seat re-ground, or an entire new assembly substituted therefor. It is particularly noted that the construction herein shown causes no wear on the intake chamber as the shoulder 15 therein merely supports the head and does not act as a valve seat, as has been the practice heretofore.

What I claim and desire to secure by Letters Patent is:

1. A valve assembly adapted to be mounted in the valve intake chamber of a gas engine having a valve seat therein including, a head mounted on the valve seat of said engine, and a plurality of valve members movable in the head and operable by the engine suction for controlling the admission of fuel to said engine.

2. A valve assembly adapted to be mounted in the valve intake chamber of a gas engine having a valve seat therein including, a valve head mounted on the valve seat of said engine and arranged to close the fuel intake opening within the chamber and having a plurality of ports therein, and a valve member closing each port and adapted to be moved by the engine suction to open the port, whereby fuel is admitted to the engine through said ports.

3. A valve assembly adapted to be mounted in the valve intake chamber of a gas engine having a valve seat therein including, a valve head mounted on the valve seat of said engine and arranged to close the fuel intake opening within the chamber and having a plurality of ports therein, a valve member closing each port and adapted to be moved by the engine suction to open the port, whereby fuel is admitted to the engine through said ports, and means for limiting the movement of said valve members.

4. A valve assembly adapted to be mounted in the valve intake chamber of a gas engine having a valve seat therein including, a valve head mounted on the valve seat of said engine and secured within the chamber and closing the fuel intake opening therein, said head having a plurality of ports therein through which fuel may flow to the engine, and a plurality of valve members one for each port arranged to close said ports, and spring pressed means for urging said valve members to a closed position, said members being moved to their open position by the suction of the engine.

5. A valve assembly adapted to be mounted in the valve intake chamber of a gas engine having a valve seat therein including, a valve head mounted on the valve seat of said engine and secured within the chamber and closing the fuel intake opening therein, said head having a plurality of ports therein through which fuel may flow to the engine, a plurality of valve members one for each port arranged to close said ports, spring pressed means for urging said valve mem-

bers to a closed position, said members being moved to their open position by the suction of the engine, and means secured to the head and overhanging the valve members for limiting the 5 movement of the members.

6. The combination with a gas engine valve chamber having a transverse partition therein and an intake opening extending through the partition, of a valve assembly including, a valve 10 head mounted in the partition and closing the intake opening therein, said head having a plurality of ports through which the fuel may flow to the engine, a plurality of valve members one for each port for closing said ports, each member 15 including a disk adapted to seat on the head to overlie one of the ports and exposed to the suction of the engine, a guide stem depending from each disk, and a coiled spring surrounding the lower end of the stem of each valve member for 20 urging the members to their closed position, said members being moved to their open position by the engine suction.

7. The combination with a gas engine valve chamber having a transverse partition therein and an intake opening extending through the partition, of a valve assembly including, a valve 25 head mounted in the partition and closing the intake opening therein, said head having a plurality of ports through which the fuel may flow to the engine, a plurality of valve members one for each port for closing said ports, each member 30 including a disk adapted to seat on the head to overlie one of the ports and exposed to the suction of the engine, a guide stem depending from each disk, means carried by the head through 35 which the stems of the members are slideable for guiding the members in their movement, and resilient means for urging the members to their closed positions, said members being moved to 40 their open positions by the engine suction.

8. The combination with a gas engine valve chamber having a transverse partition therein and an intake opening extending through the partition, of a valve assembly including, a valve 45 head mounted in the partition and closing the intake opening therein, said head having a plurality of ports through which the fuel may flow to the engine, a plurality of valve members one for each port for closing said ports, each member 50 including a disk adapted to seat on the head to overlie one of the ports and exposed to the suction of the engine, a guide stem depending from each disk, a coiled spring surrounding the lower 55 end of the stem of each valve member for urging the members to their closed position, said members being moved to their open position by the engine suction, and means secured to the head and overhanging the valve members for limiting the movement of the members.

9. The combination with a gas engine valve chamber having a transverse partition therein and an intake opening extending through the partition, of a valve assembly including, a valve 60 head mounted in the partition and closing the intake opening therein, said head having a plurality of ports through which the fuel may flow to the engine, a plurality of valve members one for each port for closing said ports, each member 65 including a disk adapted to seat on the head to overlie one of the ports and exposed to the suction of the engine, a guide stem depending from each disk, means carried by the head through 70 which the stems of the members are slideable for guiding the members in their movement, resil-

ient means for urging the members to their closed positions, said members being moved to their open positions by the engine suction, and means secured to the head and overhanging the valve members for limiting the movement of 5 members.

10. The combination with a gas engine valve chamber having a transverse partition therein and an intake opening extending through the partition, of a valve assembly including, a valve 10 head mounted in the partition and closing the intake opening therein, said head having a plurality of ports through which the fuel may flow to the engine, a plurality of valve members one for each port for closing said ports, each member 15 including a disk adapted to seat on the head to overlie one of the ports and exposed to the suction of the engine, a guide stem depending from each disk, an axial shank depending from the head and disposed between the depending 20 stems of the valve members, a plurality of radially extending guide collars on the lower end of the shank through which the stems extend to guide the valve members in their movement, and means for limiting the movement of the valve 25 members as they move to an open position.

11. The combination with a gas engine valve chamber having a transverse partition therein and an intake opening extending through the partition, of a valve assembly including, a valve 30 head mounted in the partition and closing the intake opening therein, said head having a plurality of ports through which the fuel may flow to the engine, a plurality of valve members one for each port for closing said ports, each 35 member including a disk adapted to seat on the head to overlie one of the ports and exposed to the suction of the engine, a guide stem depending from each disk, an axial shank depending from the head and disposed between the depending 40 stems of the valve members, a plurality of radially extending guide collars on the lower end of the shank through which the stems extend to guide the valve members in their movement, and resilient means surrounding the 45 stems for urging the valve members to their closed positions, said members being moved to their open position by the engine suction.

12. The combination with a gas engine valve chamber having a transverse partition therein and an intake opening extending through the partition, of a valve assembly including, a valve 50 head mounted in the partition and closing the intake opening therein, said head having a plurality of ports through which the fuel may flow to the engine, a plurality of valve members one for each port for closing said ports, each member 55 including a disk adapted to seat on the head to overlie one of the ports and exposed to the suction of the engine, a guide stem depending from each disk, an axial shank depending from the head and disposed between the depending stems of the valve members, a plurality of radially extending guide collars on the lower end of the shank through which the stems extend to guide 60 the valve members in their movement, resilient means surrounding the stems for urging the valve members to their closed positions, said members being moved to their open position by the engine suction, and means secured to the head and overhanging the valve members for 65 limiting the movement of the members.
